UNITED STATES PATENT OFFICE.

JOHN J. MOORE, OF NEWPORT, RHODE ISLAND, ASSIGNOR TO THE GOVERNMENT OF THE UNITED STATES.

AIR-FLASK JOINT.

Application filed September 10, 1920. Serial No. 409,490.

To all whom it may concern:

Be it known that I, JOHN J. MOORE, a citizen of the United States, residing at Newport, Rhode Island, have invented new and useful Improvements in Air-Flask Joints, of which the following is a specification.

This invention relates to improvements in torpedoes and more particularly to an improved joint between the sections of the torpedo shell.

One of the objects of the present invention is to provide a simple and practical means of connecting two parts of the torpedo shell. Another object is to provide an improved joint between the air flask and the after-body of the torpedo which will be substantially air and water tight.

A further object is to provide an improved structure of torpedo shell adjacent the air flask and water compartment of a torpedo which will be less expensive to manufacture or construct than the present arrangement and which will be more reliable and efficient in use and operation.

A further object is to provide an improved joint between the air and water flasks of a torpedo adapted to fully withstand the high pressures to which it is subjected and positively prevent moisture reaching the filleted corners thereby causing corrosion which will otherwise weaken the flask.

With these and other objects in mind attention is directed to the accompanying sheets of drawings wherein Figures 1, 2, 3 and 4 are longitudinal sectional views of the joint of the air flask and after-body at their point of connection taken at different points about the circumference of the torpedo.

Figure 5 is a longitudinal section of the parts before being connected.

Figure 6 is a detail view.

As is well known to those skilled in the art the central part of a torpedo constitutes the air flask as it is called, that is, a relatively large chamber adapted to contain air under high pressure, or approximately 4000 pounds and immediately behind this air flask are the water and alcohol flasks, the water being used in connection with the compressed air and alcohol spray to cool the burner yet at the same time be converted into super-heated steam thereby materially aiding in the propulsion of the torpedo as it passes out with the products of combustion from the combustion flask to the turbines.

Generally the air flask is provided with a separate head separating the air flask from the water flask. It has been an exceedingly difficult task to so fit and machine the parts in assembling to prevent leakage of compressed air into the water flask thus forcing a certain amount of water into the combustion flask flooding the latter and producing what is known as a "cold shot." The present invention overcomes this objection among others and definitely provides a positive seal between the air flask and water flask and also permits a more ready assembling of the parts and a tighter joint after the parts are assembled whereby leakage of the air from the flask is positively prevented.

With this explanation in mind, attention is directed to the accompanying sheets of drawing wherein 10 denotes the forward end of the after-body of a torpedo of standard construction provided with a bulkhead only a portion of which is indicated at 11 positively separating the air flask indicated at 12 directly from the water flask. The air flask body indicated at 13 is provided with threads 14 adapted to coact with the threads 15 on the inner surface of the after-body 10. An outwardly extending flange 16 on the central part of the torpedo coacts with a recess 17 at the forward end of the after-body thus making a tight joint at this point.

In order to positively prevent leakage three rings preferably of lead or other soft material are positioned at the points 18, 19 and 20 as indicated in Figure 1. The two rings 18 and 19 are relatively flat and coact between the ends of the threaded members as shown. The ring 20, however, is counter-sunk in an annular groove as shown in Figure 5 and formed as a part of the thread so as to coact with the member 13. After the parts are assembled a series of set screws 21 are placed in the tapped out holes 22, Figure 5, and screwed down with sufficient pressure to force the soft metal 20 into place all around the torpedo body thus positively insuring an absolutely air tight joint. When the parts are assembled the joint on the surface of the flask is discernible only upon very close inspection. The joint prevents any air leaking from the flask to the water compartment and any other leak occurring may be overcome by tightening the screws on

the lead packing ring. When once assembled it is intended that the joint will never be broken. An inspection of the inside of the flask at the forward end only is required 5 thus eliminating the repeated scraping and grinding in the after-head now necessary with constructions in use. If desired lead pellets 23 may be introduced between the set screws and packing member as indicated in Figure 6 thus lessening the chance 10 of the set screw being turned down on to the coacting member.

The invention is of simple and practical construction reliable and efficient in use and 15 operation and is believed to accomplish among others all of the objects and advantages herein set forth.

Without further analysis, the foregoing will so fully reveal the gist of this invention that others can by applying current knowledge readily adapt it for various applications without omitting certain features that, from the standpoint of the prior art, fairly constitute essential characteristics of 20 the generic or specific aspects of this invention, and, therefore, such adaptations should 25 and are intended to be comprehended with-

in the meaning and range of equivalency of the following claim.

What I claim is:—

In a torpedo construction, in combination, 30 a central body and an end body each provided with coacting threaded surfaces whereby the parts may be screwed together, the outer of said parts being provided intermediate the ends of the threaded portion with a circumferential groove and a soft metal packing ring mounted in said groove and with its exposed surface formed to engage the threads of the other member 40 when the parts are screwed together, a series of set screws mounted in the outer surface of the outer threaded member and coacting at their inner ends with said soft packing ring whereby after the parts are 45 assembled the set screws may be tightened to securely seal the joint and packing rings positioned at the ends of the threaded surface adapted to be clamped as the parts are screwed together.

Signed at Newport, Rhode Island, this 50 26th day of June 1920.

JOHN J. MOORE.
